BY

ATTORNEY

UNITED STATES PATENT OFFICE.

EDWARD VORSTER, OF NEW ORLEANS, LOUISIANA.

PACKING BOTTLES AND SIMILAR ARTICLES.

SPECIFICATION forming part of Letters Patent No. 242,493, dated June 7, 1881.

Application filed October 11, 1880. (No model.)

To all whom it may concern:

Be it known that I, EDWARD VORSTER, a resident of the city of New Orleans, parish of Orleans, and State of Louisiana, have invented 5 a certain new and useful Improvement in Packing Bottles, Jars, and other like Articles; and I do hereby declare the following to be a full, clear, and correct description of the same, reference being had to the annexed drawings, 10 making a part of this specification.

Figure 1 represents a top view of a case, the cover of which is removed in order to exhibit the packing of bottles, &c. Fig. 2 is a vertical longitudinal section through the line *a a* there- 15 of, but not showing the bottle in section. Fig. 3 is a vertical cross-section through the line *b b* of Fig. 1, and Fig. 4 a section through the horizontal line *c c* of Fig. 2. To the right and left of Fig. 4 are representations of bottles, the 20 necks of which are provided with protectors.

As the title indicates, the object of my invention is to pack bottles, jars, and other articles having necks narrower than their bodies, or having one end of less diameter than the 25 other, in boxes or cases in such manner that a greater number of such articles shall be contained in a box or case of given size.

The nature of my invention consists in packing the bottles, jars, and other like articles in 30 vertical and inverted positions, and in rigidly securing the same by means of keys and dividing as well as sustaining pieces; also, in separating the articles from one another by means of pieces of thick soft paper or other suitable 35 material placed between or around them, as will be hereinafter more fully set forth, and specifically pointed out in the claims.

To more fully understand the invention reference must be had to the accompanying drawings, on which—

A represents an ordinary case, in which the bottles or other articles to be packed are placed in a vertical position, as at B B, &c., space being left between each longitudinal and trans- 40 verse row for the reception of the dividing and sustaining strips *d e*, the latter, *e*, placed at right angles to the former, and the height of the two combined being equal to the height of

the keys *f g*, that are dropped in at one side and end of the box. These keys not only serve 50 to secure the above articles, but also act as sustaining-pieces for a side and end row of the second series, the latter inverted, and so arranged that their necks or smaller diameters shall pass between the necks or smaller diameters 55 of those already in position, and rest on the sustaining-pieces above mentioned.

To separate the articles from one another strips of thick soft paper *h i*, or other suitable material, are placed between the first series 60 previous to the insertion of the second series, or the heads and necks of each are furnished with protectors, as shown at *k l*, or *m*.

Duplicates of the sustaining and dividing pieces are then inserted in position between 65 the ends of the last series, after which duplicate key-pieces are inserted at right angles to the same, and diagonally opposite to those previously mentioned, when the box is ready for closing.

If desired, sheets of thick soft paper or other material may be placed around the inside of the case and beneath and above the articles 70 that are packed therein.

Having described my invention, what I claim 75 as new, and desire to secure by Letters Patent, is—

1. The combination of two or more rows of bottles resting on their base, two or more rows of inverted bottles, the necks of the upright 80 alternating with the necks of the inverted bottles, and two series of partitions and keys maintaining in position the upright and the inverted rows of bottles, substantially as set forth.

2. The means hereinbefore described of 85 packing bottles and similar articles for shipment, consisting of a box or case, dividing and sustaining strips *d e*, keys *f g*, and the soft thick paper *h i*, all arranged in the manner as described.

In testimony whereof I have hereto signed my name.

EDWD. VORSTER.

In presence of—

EUG. KROST,
PETER J. FINNEY,
